CLAIM

We claim the ornamental design for a valve, as shown and described.

DESCRIPTION

FIG. 1 is a top, rear, left perspective view of the claimed design;

FIG. 2 is a bottom, front, right perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

In the drawings, the broken line showing portions of the valve depicts environment and forms no part of the claim.
